UNITED STATES PATENT OFFICE.

MERCHANT STODDARD, OF CHEHALIS, WASHINGTON.

BOILER.

1,149,303.

Specification of Letters Patent. Patented Aug. 10, 1915.

Application filed April 2, 1915. Serial No. 18,753.

To all whom it may concern:

Be it known that I, MERCHANT STODDARD, a citizen of the United States, residing at Chehalis, in the county of Lewis and State 5 of Washington, have invented a new and useful Boiler, of which the following is a specification.

The present invention appertains to boilers, and aims to provide a boiler having 10 novel and improved steam generating means, whereby the steam may be generated quickly and in comparatively large quantities within a short time.

It is also within the scope of the invention to provide a boiler embodying a unique assemblage of the component parts, whereby the utility of the boiler is enhanced, and whereby the structure is comparatively simple and inexpensive, may be readily separated for purpose of cleaning, repair or replacement, and will be thoroughly efficient and practical in use.

With the foregoing and other objects in view, which will appear as the description 25 proceeds, the invention resides in the combination and arrangement of parts and in the details of construction hereinafter described and claimed, it being understood that changes in the precise embodiment of 30 the invention herein disclosed can be made within the scope of what is claimed without departing from the spirit of the invention.

The invention is illustrated in the accompanying drawing, wherein:—

35 Figure 1 is a horizontal section of the improved boiler, portions being broken away. Fig. 2 is a vertical section of the boiler, portions being broken away. Fig. 3 is a front end view of the boiler, portions being broken 40 away. Fig. 4 is an enlarged sectional detail illustrating one of the water nozzles and accompanying parts.

In carrying out the invention, the boiler 45 comprises a casing 1 of brick work or other suitable material, and inclosing the combustion chamber 2. A suitable grate 3 is supported within the casing 1 for supporting the coals, and an ash pit 4 is provided below the grate 3. The front or forward end of 50 the casing 1 is provided with fuel and ash doors 5 and 6 above and below the grate, respectively.

The steam generating means embodies a 55 plurality of pipes, of which there may be any suitable number, according to the capacity of the boiler, and each of these pipes

embodies a series or set of vertically spaced parallel longitudinal pipe sections 7 which have their ends engaged through the front and rear ends of the casing 1, and which 60 have their ends connected by U-couplings 8 located upon the exterior of the ends of the casing. The upper or inlet pipe sections 7 of the steam generating pipes have their forward ends extending through the front end of the casing 1, and caps 9 are threaded upon the said ends of the upper or inlet pipe sections 7. The lower or discharge pipe sections 7 have their forward ends projecting through the front end of the casing and T- 70 couplings 10 have their arms or branches threaded upon the said ends of the lower pipe sections 7, and the ends of the couplings 10 are connected by pipe sections 11. The couplings 10 and pipe sections 11 co- 75 operate to provide a transverse steam chamber or pipe upon the front end of the casing, one end of the steam chamber or pipe being provided with a valve 12, and a steam pipe 13 being connected to the other end of said 80 transverse steam pipe or chamber. The pipe 13 is connected to a water tank or reservoir 14 located in rear or above the boiler, whereby the water will be delivered by gravity, as 85 hereinafter set forth to the steam generating pipes. The pipe 13 is connected to the tank or reservoir 14 above the water level therein, and the water level is slightly above the upper pipe sections 7. That end of the transverse steam chamber or pipe 10—11 to 90 which the pipe 13 is connected, is preferably provided with a depending branch 15 having a valve 16. A pipe 17 extends from the upper portion of the tank or reservoir 14 to allow the steam to be conveyed to the 95 engine, radiators, or other device or devices utilizing the steam.

The water supplying means includes an inclined pipe 18 having its lower end attached to the lower portion of the tank or 100 reservoir 14, and the pipe 18 extends through the combustion chamber 2 of the casing 1, and out through the front end of the casing. The forward end of the pipe 18 is provided with a transverse portion 19 disposed above the couplings 10 and pipe sections 11, and having T-couplings 20 interposed therein. Pipe sections 21 are engaged to the upstanding arms or branches of the couplings 20, and elbows 22 are connected to the upper ends of the pipe sections 21. Nozzles 23 are connected to the 110

elbows 22, and are threaded or otherwise engaged through the caps 9 to project into the inlet ends of the upper pipe sections 7. The nozzles 23 each embodies a pair of sections 5 connected by a union 24, which allows the nozzle sections to be separated when desired. The water pipe 18 is provided with a controlling valve 25, and with a discharge valve 26.

10 In operation, after the fire is lighted within the combustion chamber 2, the controlling valve 25 is opened to allow the water to flow from the tank or reservoir 14 into the upper pipe sections 7 of the steam generating pipes, 15 the water flowing from the portion 19 of the pipe 18 up through the pipe sections 21 and nozzles 23 into the upper pipe sections 7. The water flowing through the pipe 18 will receive its initial heat since the pipe 18 20 is disposed within the combustion chamber 2, and the pipe sections 7 being heated within the combustion chamber will generate the steam quickly therein. The steam and unvaporized water will flow downwardly 25 within the steam generating pipes, and pass back and forth through the pipe sections 7 within the combustion chamber so that the remaining water will be generated into steam, and the steam will be super-heated 30 in the lower pipe sections 7. The steam will then be discharged from the lower pipe sections into the couplings 10 and through the said couplings and pipe sections 11 to the steam pipe 13. From the pipe 13 steam is 35 discharged into the tank or reservoir 14, to create a pressure on the water. The steam may be drawn from the tank or reservoir 14 through the pipe 17, or the steam may be taken from the branch 15 of the pipe 13.

40 The nozzles 23 inject the water in jets or streams into the upper pipe sections 7, and the water will be heated quickly within the pipe sections 7. The back pressure of the steam generated within the pipe sections 7 45 upon the water will be equalized, since the discharge ends of the steam generating pipes are connected by means of the pipe 13 to the tank or reservoir 14 above the surface of the water. Consequently, the steam 50 will not force the water back into the tank, but will force the water into the boiler, assisted by the gravitation of the water when the controlling valve 25 is opened. The flow of water may be regulated by the valve 25 55 according to the amount of steam desired. Steam may also be drawn from the valve 12, and the said valve is also useful since when the boiler is idle, the valve 12 may be opened or removed to enable the couplings 10 and

pipe sections 11 to be examined on the interior thereof.

It will be noted that the pipe sections 7 have their joints or connections located on the outside of the boiler casing, in order that the joints may be readily examined, 65 and whereby leaks can be quickly detected. Furthermore, the pipe sections 7 may be readily removed and replaced should they be burnt out. Thus, to remove the upper pipe sections 7, the sections of the nozzles 23 are separated by unscrewing the unions 24, and the pipe sections 21 may then be swung forwardly and downwardly with the T-couplings 20. The caps 9 may then be readily unscrewed from the upper pipe sections 7, and the upper pipe sections may then be unscrewed from the respective rear U-couplings 8. The said U-couplings 8 may then be unscrewed from the second pipe sections 7 to enable the said pipe sections to be 80 unscrewed from the front U-couplings 8. This may be continued until all the pipe sections 7 are detached, so that they can be readily withdrawn from the casing and replaced. In the same manner, the front 85 and rear ends of the pipe sections 7 may be opened for purpose of examination or repair.

Having thus described the invention, what is claimed as new is:—

90 A boiler comprising a casing, a plurality of steam generating pipes therein and each comprising a series of vertically spaced pipe sections having their ends extending through the casing, and couplings connecting the 95 ends of said pipe sections, a steam discharge pipe connected to the ends of the lower pipe sections outside of the casing, caps engaged to the ends of the upper pipe sections upon the exterior of the casing, a water supply 100 pipe having a transverse portion upon the exterior of the casing and couplings adapted to be swung, pipe sections connected to the last mentioned couplings and projecting angularly from said portion of the water supply pipe, and nozzles carried by the last mentioned pipe sections and projecting angularly therefrom, the nozzles being engaged through said caps and each comprising sections and a union detachably connecting them.

105 In testimony that I claim the foregoing as my own, I have hereto affixed my signature in the presence of two witnesses.

MERCHANT STODDARD.
